UNITED STATES PATENT OFFICE.

RUFUS E. ZIMMERMAN, OF PITTSBURGH, PENNSYLVANIA, ASSIGNOR TO AMERICAN SHEET AND TIN PLATE COMPANY, OF PITTSBURGH, PENNSYLVANIA, A CORPORATION OF NEW JERSEY.

TINNING APPARATUS.

Application filed December 12, 1924. Serial No. 755,498.

This invention relates to the manufacture of tin plate, and more particularly to a novel tinning apparatus which will provide for scouring or scrubbing the plates while they are immersed in the tin bath to remove any foreign matter carried on the surfaces of the plate and thereby provide a better coating of tin on the plates than has been possible with the apparatus heretofore in use.

10 It has been discovered that pin holes and small uncoated areas on tin plate are due in a large part to the lack of clean metal to metal contact during the tinning process. Any dirt, dried flux or other foreign substances which become attached to the surface of the base keeps the molten tin away from the area affected, and leaves a defect in the coating. I have also discovered that if during the early stages of the tinning operation, 20 and while the flux is still performing its normal function, there is provided a mechanical scouring or scrubbing action on the surface of the plates, the dirt, particles of dried flux and other foreign substances will be removed 25 and a perfect coating will be formed.

In the drawings,

Figure 1 is a sectional side elevation on the line I—I of Figure 3 showing a tinning pot constructed and arranged in accordance with 30 my invention.

Figure 2 is a sectional side elevation on the line II—II of Figure 3, showing the gearing by which the scouring or scrubbing rolls are driven.

35 Figure 3 is a sectional end elevation, the section being taken on the irregular line III—III of Figure 2.

Figure 4 is a sectional side elevation on the line IV—IV of Figure 3, showing further 40 details in the driving mechanism for the scouring or scrubbing rolls.

The apparatus shown in the accompanying drawings consists of a standard and well known form of tin pot A, which is separated 45 transversely by a vertical wall or partition 2 into compartments B and C. The lower edge of this partition 2, which terminates above the bottom of the tinning pot, and the upper edge of a rib or projection 3 on the bottom of the pot, define the width or ver-

tical dimension of a narrow passage or opening D through which the plates, while submerged in the bath of molten tin, pass from the compartment B into the compartment C of the pot A.

55 The side walls of the compartment C at the exit end of the pot are extended upwardly, so that this compartment is considerably deeper than the compartment B, this old and well known construction making it possible to maintain a body of oil, generally palm oil, 60 of the requisite depth or thickness, on top of the molten tin in the compartment C. The levels at which the bath of molten tin is maintained in the pot are indicated by the line 65 X—X in Figure 1 of the drawings, and a thin layer of flux H is maintained on top of the tin in the compartment B on the entrance end of the pot. Due to the weight of the body of oil on the tin in the compartment C, the 70 level of the tin in this compartment is somewhat lower than that of the molten bath in the compartment B.

75 Located immediately above the upper edge of the compartment B, at the plate entering side of the tinning pot, is a pair of spring pressed feed rollers E composed of rollers 5 and 6, which are arranged to move the pickled and washed plates forwardly and downwardly into the tin pot at an angle to the horizontal, through the layer of flux H into the molten tin in the compartment B.

80 Positioned within the compartment B below the tin level are two pairs of feed rollers F and G, consisting of rollers 8 and 9 and 10 and 11, respectively. The rollers of each of said pairs of rollers F and G are adapted to have differential surface speeds and thereby produce a scouring or scrubbing action on the surfaces of the plates passing therebetween, 85 since such plates will move between said rollers at a mean speed relative to the surface speeds of said rollers.

89 It will be understood that rollers 8 and 9 and 10 and 11 may be of different diameters in order to provide the differential surface speeds, or they may be of the same diameter and be driven at different speeds as illustrated in the drawings.

In the apparatus illustrated in the draw- 100

ings, a drive shaft 14 is arranged transversely of the pot A, and is provided with a bevel gear 15 which meshes with a bevel gear 16 on a shaft 17, which extends along the side of the machine and carries bevel gears 18 and 19 which mesh with bevel gears 20 and 21 on the shafts of rollers 5 and 8, respectively.

The roller 5 is provided at its end opposite the gear 20 with a pinion 23 which meshes with a pinion 24 on the roller 6, so that both rollers 5 and 6 are positively driven.

The roller 8 is provided with a pinion 25 on its end opposite the gear 21 which pinion is in mesh with a smaller pinion 26 on the shaft of roller 9 so that the rollers 8 and 9 are both positively driven, but the roller 9 will have a materially greater surface speed than the roller 8. The pinion 25 preferably has twenty-two teeth while the pinion 26 has twenty fifteen teeth.

The roller 10 is provided with a small pinion 27 of the same size as the pinion 26 and meshes with a pinion 28 on the roller 11 which preferably is of the same size as the pinion 25. An intermediate pinion 29 is mounted between and meshes with the pinion 25 on the roller 8 and pinion 27 on the roller 10, so that all four of the feed rollers 8, 9 and 10, 11 are positively driven from the shaft 17, and the rollers of each of the pairs F and G are driven at differential surface speeds.

It will also be noted that the rollers 8, 9, 10 and 11 are located so close to the flux H, that enough flux will be carried down on the surfaces of the plates to maintain the rollers F and G in working condition. That is supply enough flux to prevent tin on the rollers from flaking off and in this way bare the surfaces of the rollers, which would result in making defectively coated plates.

Three sets of feed-out rollers I, J, and K are provided which are located within the body of oil maintained on top of the tin in the compartment C of the pot A. The sets of rollers I, J, and K are formed of rollers 30, 31; 32, 33; and 34, 35, respectively, which are arranged to not only feed the tinned plates out of the tin pot, but also act to squeeze off surplus tin from the smooth alloy coated surfaces of the plates passing upwardly out of the tinning pot. The body of oil in which these rollers are submerged acts to prevent the molten coating on the surfaces of the plates from contacting with the atmosphere, until after the excess coating has been removed.

The sets of rollers E, F, G, I, J, and K are so located and spaced within the pot that the plate being tinned will be engaged in the bite of the succeeding set of rollers before it leaves the bite of the preceding set.

In operation, the plates will be fed singly into the bite of the rollers E, either by hand or by any known form of mechanical feeding mechanism. The rollers E will engage and

feed the plates downwardly and forwardly through the flux H, and the tin in the compartment B, into the bite of the rollers G, which in turn will feed them into the bite of the rollers F. The rollers of each of the pairs 70 of rollers G and F, due to their differential surface speeds will cause the plates to move therethrough at a mean speed relative to the surface speeds of said rollers, thereby causing the rollers to rotate on the surfaces of the 75 plates and scour or scrub said surfaces.

The scouring or scrubbing action of the rollers G and F will smooth the plate surfaces and remove any particles of dirt, dried flux, or other foreign matter adhering to the plate 80 surfaces, which matter if it were not removed would interfere with the coating of the plates and cause the formation of pin holes and other defects.

The rollers G and F are located sufficiently 85 close to the flux that the flux is still active on the plates, and serve to clean the plates at a sufficiently early stage in the tinning operation that the plates may take on sufficient tin to coat the places from which the foreign matter is removed after the areas thus cleaned 90 pass from between the rollers G and F.

The rollers G and F, feed the plates forwardly from the compartment B into the compartment C, where the tinning operation 95 is completed, and then into the bite of the feed-out rollers I, which then feed the plates upwardly through the oil and remaining feed-out rollers J and K and out of the pot A.

By the inclusion of the step of scouring or 100 scrubbing the plate surfaces in the early stages of the tinning operation the tinned surfaces of the plates are materially improved, and pin holes and other defects due to foreign matter adhering to the plate surfaces 105 are eliminated.

While I have shown and described one specific embodiment of my invention, it will be understood that I do not wish to be limited thereto, since various modifications may be 110 made without departing from the scope thereof as defined in the appended claim.

I claim—

A tinning apparatus comprising, in combination, a tinning pot having a molten tin bath 115 therein, a transverse wall separating said pot into compartments, said wall having an opening below the upper surface of the tin bath forming a passage through which plates being tinned are transferred from one compartment to the other, a body of flux in one and a body of oil in the other compartment, said flux and oil bodies being supported on the upper surface of said tin bath, feed-in rollers located above the level of the tin bath and 120 flux in the flux containing compartment and flux in the flux containing compartment and adapted to feed plates into and through the flux and into the tin bath, at least one other pair of feed-rollers in said flux containing compartment and submerged in the tin bath, 130

each of the rollers of said last named pair of rollers having a differential surface speed, and being adapted to engage with and feed the plates being tinned through the tin bath 5 and into the body of oil, and said rollers due to their differential surface speed being adapted to scour or scrub the surfaces of the plates passing between them and thus remove foreign matter therefrom, and feed out rollers in said body of oil adapted to engage and feed 10 the plates out of the oil.

In testimony whereof I have hereunto signed my name.

RUFUS E. ZIMMERMAN.
